(57) **CLAIM**

The ornamental design for an air cylinder cart frame, as shown and described.

DESCRIPTION

FIG. 1 is a perspective view of an air cylinder cart frame showing my new design;

FIG. 2 is a front elevation view thereof;

FIG. 3 is a back elevation view thereof;

FIG. 4 is a side elevation view thereof, wherein the opposite side is a mirror image thereof;

FIG. 5 is a top plan view thereof;

FIG. 6 is a bottom view thereof;

FIG. 7 is a perspective view thereof, shown in a first alternate position;

FIG. 8 is a perspective view thereof, shown in a second alternate position;

FIG. 9 is a perspective view thereof, shown in a third alternate position;

FIG. 10 is a perspective view thereof, shown in a fourth alternate position; and,

FIG. 11 is a perspective view thereof, shown in a fifth alternate position.

The broken lines of the air cylinder cart frame are for the purpose of illustrating portions of the article and form no part of the claimed design.
